Primary Examiner — John Windmuller(74) *Attorney, Agent, or Firm* — Cantor Colburn LLP**CLAIM**

The ornamental design for a wireless smart button, as shown and described.

DESCRIPTION

FIG. 1 is a front top right perspective view of a wireless smart button, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and

FIG. 7 is a bottom view thereof.

FIG. 8 is a rear bottom left perspective view thereof;

FIG. 9 is a cross-sectional view thereof, taken along line 9-9 in FIG. 6;

FIG. 10 is an exploded view of FIG. 8; and,

FIG. 11 is an exploded view of FIG. 1, in a Tag environment. The even-dash broken lines depict portions of the wireless smart button that form no part of the claimed design. The dot-dash broken lines depicting the Tag in FIG. 11 are for environmental purposes only and form no part of the claimed design.
